UNITED STATES PATENT OFFICE

EMERY G. GILSON, OF COLONIE, NEW YORK, ASSIGNOR TO GENERAL ELECTRIC COMPANY, A CORPORATION OF NEW YORK

DESIGN FOR A RAZOR BLADE SHARPENING MACHINE

Application filed December 12, 1931. Serial No. 42,047. Term of patent 14 years.

To all whom it may concern:

Be it known that I, EMERY G. GILSON, a citizen of the United States, residing at Colonie, county of Albany, State of New York, have invented a new, original, and ornamental Design for a Razor Blade Sharpening Machine, of which the following is a specification, reference being had to the accompanying drawing forming a part thereof.

The single figure of the drawing is a perspective view of the razor blade sharpening machine.

I claim:

The ornamental design for a razor blade sharpening machine as shown.

In witness whereof, I have hereunto set my hand.

EMERY G. GILSON,
